Primary Examiner — George D. Kirschbaum*Assistant Examiner* — Kendra Leslie Hamilton(74) *Attorney, Agent, or Firm* — Dunlap Bennett & Ludwig PLLC(57) **CLAIM**

The ornamental design for a teether, as shown and described.

DESCRIPTION

FIG. 1 is a perspective view of a teether showing our new design;

FIG. 2 is a front elevation view thereof;

FIG. 3 is a rear elevation view thereof;

FIG. 4 is a left side elevation view thereof;

FIG. 5 is a top plan view thereof;

FIG. 6 is a right side elevation thereof; and,

FIG. 7 is a bottom plan view thereof.

The broken lines shown in the drawings illustrate portions of the teether that form no part of the claimed design.

1 Claim, 3 Drawing Sheets(56)
